UNITED STATES PATENT OFFICE.

JOSEF FLIEGEL, OF MALLMITZ, GERMANY.

SPRING-WHEEL.

No. 849,223.

Specification of Letters Patent.

Patented April 2, 1907.

Application filed December 26, 1906. Serial No. 349,461.

To all whom it may concern:

Be it known that I, JOSEF FLIEGEL, a subject of the German Emperor, and a resident of Sprottauer Chaussée, Mallmitz, in the Empire of Germany, manufacturer, have invented new and useful Improvements in Spring-Wheels, of which the following is a specification.

This invention relates to the construction of a spring-wheel of that class wherein a comparatively rigid or unyielding rim and a spring-supported hub capable of independent movement constitute the two parts of the wheel. In connection with this arrangement known, *per se*, there are provided, according to the present invention, as means for transmitting the spring-pressure to the hub preferably lever-shaped bars actuated by the springs and supported by the rigid rim. These bars form straight abutments which engage with the periphery of the hub tangentially and support the same yieldingly. In this type of spring-wheel the hub obviously tends to assume an eccentric position in counteracting the yielding capacity of the springs serving as buffers. Now in order that for such eccentric movement the buffer-bars of the opposite side may not exert their yielding action beyond the normal limit of the central position of the hub adjustable stops are provided for limiting the movement of the bars in the yielding direction, whereas the counteractive movement of the springs is also limited.

The invention can be carried out with three or several buffer-bars, and each buffer-bar may be subject to the tension of one spring or a group of springs.

Referring to the accompanying drawings, Figure 1 is a vertical elevation of a wheel fitted with three buffer-bars in accordance with the invention. Fig. 2 is a section on line A B, and Fig. 3 is a detail of the adjustable stop.

The rigid outer rim *a* is preferably of U cross-section and is sufficiently reinforced by double-flanged extensions *a'* *a''* *a'''* so as to form without spokes a resistible wheel-frame. The hub *b*, secured to the boss on journal-shank *c*, forms with its periphery, made, preferably, of chilled steel, the engaging surface for the buffer-bars *d*, of which three are assumed in the form of construction shown in the drawings.

The buffer-bars *d* engage or contact, Fig. 1, 55 the hub *b* tangentially with straight abutments where they have to counteract the pressure of the hub tending to assume an eccentric position and are pivoted at *e* on the rim *a*, thus acting as levers. The bars *d* are 60 adapted to yield with spring-pressure directed to the center of the wheel by means of the springs *f*. These springs are mounted on radially-arranged spokes or supporting members *i*, which are linked by pivotal connection at *j* to the rim *a*. The spring-pressure is taken up by the transmitting members *h*, socketed with the supporting members *i*, the heads *k* of the members *h* being pivoted to the bars *d* at *l*. In order that the said heads 70 *k* may move with the linked bars *d* only in the plane of the wheel and be deprived of any lateral displacement, the hub *b* is provided at the front and rear sides of the wheel with a pair of disks *b'* *b''*. The heads *k* are 75 slidable between these parallel disks, thus allowing of the eccentric movement of the hub with respect to the rim *a*.

An angular stop *q* with adjusting-screw *p* is attached to each buffer-bar *d* and serves for 80 limiting the inward stroke of the latter, the screw *p* abutting against the rim, as shown in Figs. 1 and 3. The tension of the springs *f* and the position of the stop should be so regulated that the hub for its normally relieved condition is in the exact central position. The regulation by means of the adjustable stops *p* *q* enables an accurate adjustment of the springs, as well as an accurate centering of the hub, and also attains the advantage that the buffer-bars are prevented from making a surplus movement toward the center, thereby affording free play for the hub, which while sliding on the buffer-bars *d* always tends to assume the normal central 90 position. Finally the stops render each buffer-bar and each spring *f* independent of the other springs, whereby the full tension of each spring will be utilized individually for supporting the hub without this individual action 95 being affected by the other springs as the movement is limited by their stops.

The three drivers or coupling-arms *m*, whereby the rotary motion of the hub *b* is transmitted to the rim *a* in the direction of the arrow, Fig. 1, engage with bolts or rollers *n*, which are arranged on the double-flanged extensions *a'* *a''* *a'''* of the rim. Through the

instrumentality of the said drivers in a regular transmission of power of the hub to the rim takes place, provided that the former is the driving member, the latter being still capable of eccentric displacement. Thus in the event of jerks the hub counteracted by the respective spring will yield in a downward or possibly forward direction, while sliding along the abutments of the buffer-bars, and thus neutralizing the jerking effect.

Having now particularly described and ascertained the nature of my said invention and in what manner the same is to be performed, I declare that what I claim, and wish to secure by Letters Patent, is—

1. In a spring-wheel the combination of a rigid rim, an inner hub capable of eccentric movement relative to the said rim, a set of buffer-bars pivotally connected with the outer rim and having straight-faced abutments which contact tangentially with the periphery of the inner hub, a set of springs supporting yieldingly the said buffer-bars and means such as lateral hub-disks for hold-

ing the buffer-bars and springs in the plane of the wheel-rim, substantially as described and shown in the drawings.

2. In a spring-wheel the combination of a rigid rim, an inner hub capable of eccentric movement relative to the said rim, a set of buffer-bars pivotally connected with the outer rim and having straight-faced abutments which contact tangentially with the periphery of the inner hub, a set of springs supporting yieldingly the said buffer-bars, adjustable stops for limiting the movement of the buffer-bars in an inward direction and means such as lateral hub-disks for holding the buffer-bars and springs in the plane of the wheel-rim, substantially as described and shown in the drawings.

In witness whereof I have hereunto signed my name, this 7th day of December, 1906, in the presence of two subscribing witnesses.

JOSEF FLIEGEL.
